CLAIM

The ornamental design for a packaging bag, as shown and described.

DESCRIPTION

FIG. 1 is a front view of a packaging bag, showing the new design;

FIG. 2 is a rear view thereof;

FIG. 3 is a right side view thereof, the left side view being a mirror image thereof;

FIG. 4 is a top view thereof;

FIG. 5 is a bottom view thereof;

FIG. 6 is a front perspective view thereof, shown in a state of use; and,

FIG. 7 is a rear perspective view thereof.

The broken lines illustrate portions of the packaging bag that form no part of the claimed design.
